UNITED STATES PATENT OFFICE.

FORREST T. DUNHAM, OF HOQUIAM, WASHINGTON.

SHACKLE-HOOK.

1,381,405.

Specification of Letters Patent. Patented June 14, 1921.

Application filed January 5, 1920. Serial No. 349,471.

To all whom it may concern:

Be it known that I, FORREST T. DUNHAM, a citizen of the United States, residing at Hoquiam, in the county of Chehalis and 5 State of Washington, have invented certain new and useful Improvements in Shackle-Hooks, of which the following is a specification.

This invention relates to hoisting, and 10 more specifically to improvements in shackle-hooks.

The object of my invention is to provide a shackle-hook so constructed as to withstand 15 great strain, in that the stress is divided equally between two points instead of one point, and the hook so fashioned that any pull thereon will be at diametrically opposite points and in a direct line with the greatest strength thereof. Where hooks are 20 so constructed that the strain thereon is directed laterally of the metal, it tends to weakness in construction.

A further object of my invention is to 25 provide a shackle-hook especially adaptable for use in the logging industries, in moving heavy donkey engines and heavy timber. In this particular use it has been found that 30 all of the ordinary hooks heretofore used frequently catch or become entangled in brush, logs, trees, and trash of all kinds, causing a great deal of trouble, the loss of considerable time, and injury, not only to the machinery, but to the men engaged in the work. By providing a closed hook, 35 having no angular corners or sharp projections, I have overcome these difficulties and dangers.

Furthermore, I provide a positive lock 40 for the hook when inclosed position, though at the same time not departing from simplicity of construction, and operation, nor detracting from the durability of my hook.

Other objects of this invention not at this 45 time more particularly enumerated, will be clearly understood from the detailed description and drawings forming a part of this specification.

Referring now to the drawings, which 50 are merely illustrative of my invention,

Figure 1 is a side elevation of my hook in locked position.

Fig. 2 is an edge elevation of the same.

Referring further to the drawings, where- 55 in similar reference characters designate similar parts throughout the respective views, 1 designates a substantially V-shaped

keeper, having a long arm 2 and a relatively shorter arm 3, both of said arms being bifurcated and each being formed with a perforation centrally of the bifurcated portions 60 thereof. Interiorly of one side of one of the bifurcations on said shorter arm 3 is formed a circumferentially disposed groove 4, a notch 5 being cut through the outer face of said bifurcation, so as to register with said 65 groove. An eye 6 is formed transversely through said keeper at a point adjacent the apex thereof, said eye being adapted to receive one end of a hauling line.

A substantially U-shaped shackle hook 7 70 is formed with a short arm 8 and a relatively longer arm 9. Both of said arms are formed with perforations transversely therethrough near the ends thereof. The perforation through the shorter arm of said U-shaped 75 hook is adapted to register with the perforations through the bifurcations of the longer arm 2 of said keeper, and be retained in pivoted engagement therewith by means of bolt 10. The perforation through the longer arm 80 of said U-shaped hook is adapted to register with the perforations through the bifurcations of the shorter arm 3 of said keeper, and to be retained in engagement therewith by means of a lock pin 11, provided with a 85 key lug 12 adapted to register with the notch 5 in said keeper, and thence to seat within the groove 4, thereby locking the pin and the hook securely in closed position. When 90 it is desired to unlock the hook, the lock pin 11 must be turned until the key lug 12 registers with the notch 5 which leads from the groove 4 to the outer face of the bifurcation, whereupon the pin may be withdrawn and the hook released. In order that the pin 95 may not become lost and may always be handy for immediate use, I provide a ring member 13 upon the end of the lock pin 11 and fix another ring member 14 within the crotch of the U-shaped keeper, interposing 100 a flexible chain 15 between said ring members.

The utility, adaptability, and advantages of my improved form of shackle-hook being obvious, it is unnecessary to further enlarge 105 upon the same herein.

Having now described and pointed out the new and useful features of my invention, I do not limit myself to the shape of certain parts where the shape is not essential, nor 110 do I restrict myself to the exact details of construction shown and described, but mean

and intend to claim all equivalents and variations thereof not departing in principle from my invention, and falling within the purview of the appended claim.

5 What I claim is:

In a hook of the class described, a deep substantially U-shaped shackle member having a rounded smooth surface with the side faces of its terminals flattened and merging 10 gradually without shoulders at their bases into the body of said member with their free ends apertured, one arm being shorter than the other, a substantially V-shaped keeper member having a rounded smooth surface 15 and one arm longer than the other, the terminals of said arms being bifurcated edge-wise to receive the flattened ends of said shackle member and having apertures registering with the apertures in said flattened 20 ends to receive respectively a pintle and a locking pin, the apex of said keeper being

rounded to form a smooth elongated nose for forcing its way through obstructing objects without engaging them and provided with a line receiving eye, the long arm of 25 the keeper being pivotally connected with the short arm of the shackle and the short arm of the keeper detachably engaged with the long arm of the shackle, the so connected shackle and keeper members forming an 30 elongated substantially ovate member provided with an elongated longitudinally extending central opening to receive the draft and load engaging elements whereby pull exerted on said member will be at diametrically opposite points in a direct line with the greatest strength thereof, and the draft and load engaging elements held out of contact 35 with each other.

In testimony whereof I affix my signature 40 hereto.

FORREST T. DUNHAM.
